CLAIM

The ornamental design for video intercom, as shown and described.

DESCRIPTION

The patent or application file contains a least one drawing executed in color. Copies of this patent or patent application publication with color drawing(s) will be provided by the Office upon request and payment of the necessary fee.

FIG. 1 is a perspective view of the video intercom showing the first embodiment of my new and ornamental design;

FIG. 2 is a front view of FIG. 1;

FIG. 3 is a left side view of FIG. 1;

FIG. 4 is a right side view of FIG. 1;

FIG. 5 is a top view of FIG. 1;

FIG. 6 is a bottom view of FIG. 1;

FIG. 7 is a perspective view of the video intercom showing the second embodiment of my new and ornamental design;

FIG. 8 is a front view of FIG. 7;

FIG. 9 is a left side view of FIG. 7;

FIG. 10 is a right side view of FIG. 7;

FIG. 11 is a top view of FIG. 7; and,

FIG. 12 is a bottom view of FIG. 7.

The broken lines shown in the figures attached hereto are included for the purpose of illustrating portions of the video intercom that form no part of the claimed design.

1 Claim, 8 Drawing Sheets
